H. F. HARTMAN

BRUSHHOLDER CONTACT FINGER

Filed April 2, 1925

INVENTOR

Harry Francis Hartman.

BY

Wesley G. Carr

ATTORNEY

Patented Jan. 12, 1926.

UNITED STATES PATENT OFFICE.

HARRY F. HARTMAN, OF PITTSBURGH, PENNSYLVANIA, ASSIGNOR TO WESTINGHOUSE ELECTRIC & MANUFACTURING COMPANY, A CORPORATION OF PENNSYLVANIA.

BRUSHHOLDER CONTACT FINGER.

Application filed April 2, 1925. Serial No. 20,072.

To all whom it may concern:

Be it known that I, HARRY F. HARTMAN, a citizen of the United States, and a resident of Pittsburgh, in the county of Allegheny and State of Pennsylvania, have invented a new and useful Improvement in Brushholder Contact Fingers, of which the following is a specification.

My invention relates to details of construction of brush holders for current-collecting devices of electrical machines.

My invention is an improvement in brushholders of the type shown in the patent to Dobson, No. 1,533,237, granted April 14, 1925, on an application, Serial No. 726,911, filed July 19, 1924.

In particular, my invention relates to improvements in the finger member of the brushholder, whereby a material reduction 20 in the cost of manufacture is secured, difficulties are successfully overcome in the connection of sheet-metal parts, a renewable brush-engaging tip is provided of a material having far better wearing qualities than 25 the materials which are practical to use for the rest of the finger, and a material reduction in friction and in the weight of the moving parts is secured, whereby the light-pressure action of the spring is more uniform 30 in its application to the brush.

In the accompanying drawing, showing a preferred embodiment of my invention, Fig. 1 is a plan view of the finger member partly in section on the line I—I of Fig. 2,

Fig. 2 is an elevational view of the same.

Fig. 3 is an enlarged sectional view showing an intermediate stage in the manufacture,

Fig. 4 is a sectional view on line IV—IV of Fig. 2, with the helical spring and the ratchet wheel assembled with the finger member, and

Fig. 5 is a full-size elevational view of the complete brushholder assembly.

In the embodiment shown in the drawing, a brushholder unit, comprising a brushholder frame 6, is secured, by means of a clamp 7, to the frame 8 of a motor or other dynamo-electric machine. The brushholder frame 6 carries a brushholder box 9, through which extends the carbon brush 10 which bears on a commutator member or other current-collecting device 11 of the machine. Removably mounted in suitable bearings in 50 the brushholder frame 6 is a finger-support

ing shaft 12 on which is mounted the brush-engaging finger 13 of my improved construction.

My brushholder finger 13 comprises a tubular bearing member 14 surrounding the shaft 12, a separate brush-engaging tip 15 and a separate sheet-metal finger portion 16, the latter having a cup-shaped part 17 and an integral arm extension 18. The tip 15 is of T-shape and has a leg member 19 which is riveted at 20 to the arm extension 18 of the finger portion, said arm extension being preferably channel-shaped in order to receive the leg of the tip member.

In the construction illustrated in the Dobson patent, the entire finger, which I make in the three parts 14, 15, 16, was cast as a single piece. It has been found that the materials which are suitable for casting are not durable at the contact point between the tip and the top of the brush, the tip being rapidly eroded away, apparently due to the effect of the poor contact and sparking at that point. I have made the tip member removable, so that, if it does wear, it may be replaced, and, by making it removable, I have been enabled to make the tip member of more durable material, such as hard drawn copper. This material is more resistant to the effects of sparking than the sheet brass or other sheet material from which I stamp the finger portion 16.

The cup-shaped part 17 of the sheet-metal finger portion 16 has a perforation in its closed end, the material of said end being bent inwardly to form a circular flange 21 providing a cylindrical seat 22, said seat having as great length, in an axial direction, as is practical. The tubular bearing member 14 has a reduced end portion 23 forming a shoulder which is engaged by said inwardly-bent flange 21, as shown in Fig. 3.

The end of the reduced portion of the tubular member, which thus projects beyond the cup-shaped part 17, is spun over and pounded into place against the closed end of the cup portion, and is subsequently milled off to provide a smooth seat 24 of less area than the closed end of the cup portion, whereby the end thrust friction of the finger member may be materially reduced. In view of the fact that the amount of force utilized on the finger member is only about three pounds, it will be apparent that the provision of an efficient end-thrust bearing surface

is a very desirable feature in the design of the brush contact finger.

The cup-shaped part 17 and the tubular member 14 provide an annular space which is adapted to house a helical spring 25, as shown in Fig. 4. One end of the spring is bent at 26 for interlocking engagement with a perforation 27 which is tapped at an angle into the bottom of the sheet-metal finger portion 16, the location being such as to prevent, as far as possible, the ingress of dirt through said opening. The spring chamber is further closed by means of a split tubular member 28 of thin sheet material which is sprung into place within the cup-shaped portion 17, thus protecting the spring 25 from exposure at the open side of the cup portion where the arm extension 18 is formed. The spring-engaging opening 27 in the finger member is located at the side of the cup portion 17 rather than at the end, as was necessary in the cast construction shown in the above-mentioned Dobson patent, the end location in the latter being necessitated by reason of the exigencies of the casting operation. By my construction, I bring the end 26 of the spring member out of the side of the cup-shaped hub member, thereby saving space at the end, where the thrust bearing surfaces are provided.

The open end of the annular space comprising the spring chamber of the finger member is closed by a ratchet 29 which is provided with a perforation 30, for receiving the other end of the spring 25, and a hub 31, for receiving the shaft 12, as indicated in Fig. 4. The hub 31 bears against the end of the tubular bearing member 14, and a slight clearance is provided between the ratchet 29 and the open end of the cup-shaped part 17, as indicated at 32, in order to reduce friction.

The unit comprising the pressure finger 16, with the enclosed spring 25 and the juxtaposed ratchet 29, is assembled between the bearing supports of the brushholder frame 6, and the shaft 12 is inserted through the bearings in the brushholder frame and through the bearings in the tubular member 14 of the finger and in the hub portion 31 of the ratchet. The spring is placed under tension by rotating the ratchet 29, which is held in place by a spring pawl 33 which is carried by the brushholder frame 6, as shown in Fig. 5. The finger member is provided with the usual current-carrying shunt 34 for carrying the current to the frame and preventing the current from passing through the spring 25.

From the foregoing description, it will be seen that I have provided an improved design wherein the several benefits enumerated hereinbefore are secured. While I have illustrated my invention in the form at present preferred, I do not intend that the ap-

pended claims should be restricted other than as indicated by the language thereof, when read in the light of the prior art.

I claim as my invention:

1. A brushholder for electrical machines comprising a brushholder frame having a brush box and a removably mounted shaft, a laterally extending pressure finger extending over the brush box and adapted to engage the top of the brush, said pressure finger having a tubular bearing member for said shaft and a separate sheet-metal finger portion having a cup-shaped part and an arm extension, the closed end of said cup-shaped part having an inwardly bent circular flange forming a cylindrical seat, said tubular member having a reduced end portion constituting a shoulder engaged by said inwardly bent flange, the reduced end portion of said tubular member being riveted over the closed end of said cup-shaped part, a helical spring mounted around said tubular member within said cup-shaped part and having its inner end detachably secured therein, a tension-adjusting member mounted on said shaft against the open end of said cup-shaped part for totally enclosing said spring and retaining the outer end thereof, and means for holding said tension-adjusting member in a fixed angular position for maintaining said pressure finger under stress.

2. A brushholder for electrical machines comprising a brushholder frame having a brush box and a removably mounted shaft, a laterally extending pressure finger extending over the brush box and adapted to engage the top of the brush, said pressure finger having a tubular bearing member for said shaft, a separate brush-engaging tip and a separate sheet-metal finger portion having a cup-shaped part and an arm extension, said tip having a leg member fastened to the arm extension of said finger portion and being of a material more resistant to sparking at the brush contact than the material of said finger portion, the closed end of said cup-shaped part having a perforation the rim portion of which is rigidly united to said tubular bearing member, a helical spring mounted around said tubular member within said cup-shaped part and having its inner end detachably secured therein, a tension-adjusting member mounted on said shaft against the open end of said cup-shaped part for totally enclosing said spring and retaining the outer end thereof, and means for holding said tension-adjusting member in a fixed angular position for maintaining said pressure finger under stress.

3. A brushholder for electrical machines comprising a finger-supporting shaft and characterized by a finger having a hub portion on said shaft and adapted to yieldably press a brush into operative engagement

with a co-operating current-collecting device, said finger comprising an arm extending from said hub portion, and a separate T-shaped tip for contacting with the brush, and means for securing the leg of the tip to said arm, the material of said tip being more resistant to sparking at the brush contact than the material of said arm.

4. An article of manufacture comprising
10 a tubular member and a separate sheet-metal finger portion having a cup-shaped part and an arm extension, the closed end of

said cup-shaped part having an inwardly bent, circular flange forming a cylindrical seat, said tubular member having a reduced end portion constituting a shoulder engaged by said inwardly bent flange, the reduced end portion of said tubular member being riveted over the closed end of said cup-shaped part.

In testimony whereof, I have hereunto subscribed my name this 31st day of March, 1925.

HARRY F. HARTMAN.
